UNITED STATES PATENT OFFICE.

BERNARD A. SCHMITT, OF BROOKLYN, NEW YORK.

HAIR CLIPPER.

Application filed November 3, 1925. Serial No. 66,647.

The present invention relates to hair clippers wherein two toothed plates reciprocating relative to each other cut the hair at the edges of the co-acting teeth in a well-known manner.

In order to cut the hair efficiently and not pull the same, the teeth on both plates must be sharp. Of course, in use, the teeth become dull and it is necessary to re-sharpen them.

It is one of the principal aims of the present invention to provide a clipper constructed so that the blades can be removed easily and re-assembled in position in the clipper without mechanical skill.

Another object is to house the mechanism for reciprocating the blade so that it is protected from hair, dirt, etc.

Other objects and features of novelty will be apparent from the description taken in connection with the drawings, in which:

Figure 1 is a plan view of a clipper constructed in accordance with the present invention, certain parts being broken away;

Figure 2 is a side elevation of the clipper;

Figure 3 is a sectional elevation taken substantially on the line 3—3 of Figure 1, looking in the direction indicated by the arrows;

Figure 4 is a plan view of the stationary blade;

Figure 5 is a plan view of the reciprocating blade;

Figure 6 is a sectional elevation taken substantially on the line 6—6 of Figure 1, looking in the direction indicated by the arrows;

Figure 7 is a perspective view of the blade supporting end of one of the handles of the clipper;

Figure 8 is a plan view of a modified form of the invention;

Figure 9 is a sectional elevation taken substantially on the line 9—9 of Figure 8, looking in the direction indicated by the arrows;

Figure 10 is a sectional elevation taken substantially on the line 10—10 of Figure 8, looking in the direction indicated by the arrows;

Figure 11 is a plan view of the reciprocating blade;

Figure 12 is a plan view of the stationary blade; and

Figure 13 is a sectional elevation taken substantially on the line 13—13 of Figure 8,

looking in the direction indicated by the arrows.

Referring to the drawings, the clipper, in the main, comprises a pair of handles 10 and 11, a fixed blade 12, a reciprocating blade 13, a spring 14 tending to separate the handles, and a flat-headed screw 15 and nut 16 to clamp the blades together and to the support.

The handles are preferably formed from sheet metal by the punch and die process, and as indicated in Figure 1, are channel-shaped in cross section. No machining of the handles is required. This is an important feature, as the handles can be made at a small fraction of the cost of solid or cast handles which require machining. One of the handles, as 10, is extended and formed with a flat blade support 17. As clearly shown in Figure 7, one edge of this support is provided with a flange 18 formed with the spaced shoulders 19, which, as explained hereinafter, cooperate with the stationary blade to hold it against displacement in its own plane. Adjacent the edge opposite the flange, the support is provided with a pair of flat bosses 20 on which the reciprocating blade is held out of contact with the major portion of the flat surface of the support, so that the blades may be clamped under tension as explained hereinafter.

The other handle 11, at one end, has its side flanges extended to provide the ears 21 and 22. These ears, as indicated in Figure 6, are pressed together and disposed between the flanges of the handle 10 and pivotally mounted there on a pin 23 extending through the flanges of the handle 10 and said ears. In this manner the handle 11 is pivotally mounted on the handle 10 so that it may oscillate to and from said handle 10. The handles are normally forced apart by a compound coiled expansion spring 14, the ends of which fit in sockets 24 and 25 in the web portions of the handles. When the blades are removed from the clipper, the extent to which the handles may open up under the influence of the spring is limited by shoulder 26 (Figure 6) striking the portion 27 of the adjacent flange of the handle 10.

The reciprocating blade 13 is positioned against the bosses 20 on the support 17 and is provided with an end extension 28 formed with a notch 29. A pin 30 extending through the flanges of the handle 11 is dis-

posed in this notch so that oscillation of the handle 11 reciprocates the blade. A portion of the web of handle 11 adjacent the pin 30 is cut away so that the blade can be 5 removed from engagement with the pin 30.

The stationary blade 12 is positioned against the reciprocating blade so that the reciprocating blade slides between the support 17 and the stationary blade 12. The 10 stationary blade is removably secured against movement in its own plane by providing the notches 31 which engage the shoulders 19 of the flange 18. It will be seen that this blade can be removed merely by sliding it transversely on the shoulders 19.

The blades are held in close contact and clamped together and to the support by the flat-headed screw 15 and nut 16. The screw 20 15 is positioned between the bosses 20, so that when nut 16 is screwed up tightly, the flange 17 tends to be bent inwardly, between said bosses, thereby affording a springiness or tension, hitherto requiring a separate 25 spring to accomplish. Moreover, in this manner the teeth of the blades are held in tight sliding engagement, so that the most efficient cutting action is obtained. The head of the screw is provided with a lug 30 adapted to fit in the notch 32, shown in Figure 4, whereby the screw is held against rotation. The screw head is countersunk in the blade 12 so that the head is flush with the outer surface of the blade, and in order 35 to permit the blade 13 to reciprocate, the screw passes through a slot 15^a formed therein.

In order to lubricate the sliding surfaces of the blades, a thin chamber is formed in 40 the contacting surfaces of the blades wherein a thin film of oil may be carried. For this purpose, as shown in Figure 4, a portion of the surface of blade 12 adjacent the blade 13 is formed with a depression 33 which is 45 closed on all sides. Likewise the blade 13 is formed with a depression 34, the two depressions together constituting the lubricant chamber. In order to introduce lubricant into this space, the blade 13 may be provided 50 with the channels 35 which, in one position of the blade, are adapted to register with corresponding channels 36 in the flange 18 of the support.

In order to remove the blades and sharpen 55 them or replace them, it is merely necessary to unscrew the nut 16. Then the fixed blade 12 can be withdrawn laterally from the shoulders 19 and the slidible blade lifted vertically from the position shown in Figure 1.

It will be noted that it is a very easy matter to re-assemble the parts and that no mechanical skill is required for this purpose. First the slidible blade 13 is positioned on 60 the support with the notch 29 over the pin

30. Then the fixed blade 12 is positioned with its notches 31 engaging the shoulders 19, and finally the screw 15 is inserted, and the parts clamped by the nut 16.

It will be noted that the mechanism for reciprocating the blade is almost totally enclosed or housed, thus being protected against being clogged by hair or foreign matter.

Figure 8 shows another form of the invention in which the saw-tooth edges of the blades extend substantially at right angles to the length of the handles. Referring to Figures 8-13, inclusive, this form of the invention also comprises a pair of handles 41 and 42 of channel form in cross section and preferably pressed from sheet metal, as described in connection with the first form of the invention. The handle 42 is provided with an integral extension 43 which constitutes the support for the blades. As shown, adjacent this extension, the handle 41 is pivoted to the handle 42 on the pin 44. For this purpose the flanges of handle 41 at this end are pressed together, as shown in Figure 13, so that they lie within the flanges of the handle 42, and as shown in Figure 8, one of these flanges of handle 41 is extended to provide the finger 45 which engages in the notch 46 in the slidable blade 47. Because of this arrangement, oscillation of handle 41 will reciprocate the blade 47. The handles are normally forced apart by a compound coiled spring 48 the ends of which are seated in depressions 49 in the webs of the handles. As the spring is located near the pivot pin 44, the flanges on the handles partially house the same.

As shown in Figure 13, the top flange of handle 42, adjacent the pivot pin 44, is extended laterally across the handle 41, and the support portion 43, at the edges opposite the toothed edges of the blade, is flanged downwardly as indicated at 50 and 51. Parts of these flanges 50 and 51 are cut away to provide the shoulders 52 which engage in the notches 53 on the stationary blade 54.

The slidable blade 47 is positioned between the stationary blade 54 and the support 43 as shown in Figure 9, and the parts are clamped together by a flat-headed screw 55, the head of which is counter-sunk in the fixed blade 54 and provided with a lug which engages the notch 56 to hold the screw from rotating. This screw extends through the blade 54, the slot 57 in blade 47 and the support 43 which is provided with a boss 58 around the screw and against which a nut 59 is screwed. The support 43 is formed with two flat bosses 43^a like the bosses 20 of the other form, and for the same purpose.

As described in connection with the other form of the invention, the adjacent surfaces

of the blades are provided with the depressions 60 and 61 to form an oil chamber and to give added resiliency to the blades. The depression 60 of the slidable blade 47 has channels 62 leading thereto, and these channels in one position of the blade register with the channels 63 in the flanges 50 and 51 so that lubricant may be introduced to the chamber.

In order to remove the blades for sharpening or inspection or replacement, it is merely necessary to unscrew the nut 59, whereupon the fixed blade 54 may be withdrawn laterally and then the slidable blade 47 can be taken out in case it has not already fallen out.

To assemble the parts, the slidable blade 47 is placed in position against the bosses 43 of the support and with the finger 45 in the notch 46. Then the fixed blade is positioned with its notches 53 receiving the shoulders 52, and the screw 55 inserted, and the parts clamped by screwing up the nut 59.

Although two forms of the invention have been described in detail, it is to be understood that the invention is not limited to the exact details shown but includes modifications and changes which come within the scope of the appended claims.

Having thus described the invention, what is claimed as new and desired to be secured by Letters Patent is:

1. In a clipper having a pair of toothed cutters mounted for relative sliding movement on each other, the improvement comprising a closed lubricant chamber between said blades formed by a slight depression in one of said blades and a channel extending from said chamber to the outer edge of the blade for introducing lubricant into said chamber.

2. In a clipper having a pair of toothed cutters mounted for relative sliding movement on each other, the improvement comprising a closed lubricant chamber between the contacting faces of said blades formed by slight depressions in said faces and a channel extending from said chamber to the outer edge of the blade for introducing lubricant into said chamber.

3. A clipper, including in combination, a member comprising a handle and a blade support integral therewith, a stationary blade, means removably holding said blade

on said support against movement in its own plane, a second blade slidable relative to the stationary blade, means removably clamping said blades and support together whereby both blades may be removed merely by unclamping said means, a second handle pivoted on said member, means connecting said second handle and slidable blade to reciprocate the latter by oscillation of said handle, said support having a flat portion with a flange at one edge, there being a depression in at least one face of the contacting faces of the blades to provide a lubricant chamber, and channels in said flange and blade for introducing lubricant into said chamber.

4. A clipper, including in combination, a member comprising a handle and a blade support integral therewith, said blade support being provided with a substantially flat portion having a flange at one edge, a stationary blade having means on its back edge for cooperating with said flange to hold said blade against movement along its length, a second blade slidable relative to the stationary blade, means removably clamping said blades and support together whereby both blades may be removed merely by unclamping said means, a second handle pivoted on said member, and means connecting said second handle and slidable blade to reciprocate the blade by oscillation of said handle.

5. A clipper according to claim 4 wherein said holding means comprises interlocking shoulders and lugs, the lugs being on one part and the shoulders on the other.

6. A clipper according to claim 4 wherein said flange is provided with shoulders and said stationary blade is provided with lugs, said blade being removable from said flange by movement normal to the plane of the blade.

7. The clipper according to claim 4 wherein said connecting means is disposed within the pivoted handle and thereby substantially protected against foreign matter.

8. The clipper according to claim 4, wherein the support is provided with two spaced bosses against which one of the blades is clamped, said clamping means being located between said bosses.

In testimony whereof I hereunto affix my signature.

BERNARD A. SCHMITT.
